JACK FOR ELEVATING FORMS AND FLOORS
DURING THE POURING OF CONCRETEHarry Harold Norman, Superior, Wis., assignor
to Minot Builders Supply Co., Inc., a corpora-
tion of Minnesota

Application November 13, 1950, Serial No. 195,417

4 Claims. (Cl. 254—106)

1

My invention relates to jacks for elevating forms and floors during the pouring of concrete and has for its object to provide free and loose dog members engaging an abutment with one end and having a bit member to engage with its sharpened edge the side of a rod called a jack rod which is embedded in and rigidly held by the concrete as it is poured.

In practice the arrangement operates in connection with a two-part elevating member, the parts of which are separated by the introduction of compressed air between them, in combination with which are two sets of clamping bits, one of which holds one of the members stationary by engagement of the bits with the jack rod during the lifting operation, and the other of which holds the other member stationary while the second member is restored to initial relative position with the lifted member.

Free bit members unattached directly to any part of the lifting members are held by springs to engage the jack rod while the lifting action is effected by upward movement of one of the parts of the lifting member and which hold the other part stationary when the lifted part is restored to initial position is the invention of Roy I. Patterson, whose applications Ser. No. 87,632 and No. 151,060 are pending in the Patent Office and have been assigned to the assignee of my invention.

I have discovered a novel manner of mounting the bits and holding them with springs, which is in a high degree efficient and dependable and which simplifies and renders more advantageous the free bit structure in the following particulars:

Two springs instead of one spring are mounted so as to exert the force of both springs uniformly across the body of the bit, thus insuring increased power of pull on the bit and uniform distribution of pull.

The springs are so mounted that they exert their pressure upon the bits in a plane nearly parallel to the axis of the jack rod, thus having a much more powerful torque of pull upon the swinging bits.

Radially extended parallel channel members are formed on the lower one of the movable lifter members and the springs are attached to transverse ribs extending between the channel members, said ribs all lying at the same radial distance from the center of the jack rod when the lifting device is positioned thereon. The ribs for one set of bits extend outwardly a considerable less distance than the ribs for the other set of bits.

2

The springs are connected to the members outwardly extending from the sides of the bits by means of a loop of the spring material having a gap so that the springs can be readily and easily disconnected from the bits and the bits removed for sharpening, repair or exchange.

Although the springs operate upon sets of bits of different lengths, all of the springs mounted in the above manner are of the same length which makes possible the use of a single length of springs for all of the bits.

It is an object of my invention, therefore, to employ for holding the bits two springs mounted in parallel relation and connected to ribs on the lower plate of the lifting device, which are of different lengths but lie substantially in a circle.

It is a further object of my invention to have radially extended channel members formed on the lower one of the movable lifter members and to have transverse ribs secured to and between the channel members, the ribs for one set of bits extending outwardly a considerable less distance than the ribs of the other set of bits.

It is a further object of my invention to provide pairs of springs connected to each of the several ribs, each of said pairs of springs extending outside of a clamping bit and being connected to members rigidly secured to the clamping bit and extending transversely outside the limits thereof.

It is a further object of my invention to have the pairs of springs employed for each clamping bit connected to a transverse rib at one end and connected to the bits by means of a loop of the spring material running about members extended laterally from the sides of the clamping bit, said loop having an opening whereby the springs may readily be released from the bits and the bits withdrawn for sharpening, re-pair or renewal.

It is a further and important object of my invention to form the springs for all of the bits of exactly the same length even though one set of bits is longer than the other set.

The full objects and advantages of my invention will appear in connection with the specification hereinafter appended, and the novel features of the invention by which the advantageous and useful results above noted are obtained will be particularly pointed out in the claims.

In the drawings illustrating an application of invention in one form.

Fig. 1 is a diametrical sectional elevation view 55 of a lifting device with my invention applied

thereto showing relations of the bits, springs and the two members making up the lifting device.

Fig. 2 is a sectional plan view viewed from below taken on line 2—2 of Fig. 1.

Fig. 3 is a sectional detail elevation view taken on line 3—3 of Fig. 2.

Fig. 4 is a sectional elevation view similar to Fig. 3 taken on line 4—4 of Fig. 2.

Fig. 5 is an underside plan view of the lower plate of the lifting device.

Fig. 6 is a sectional view taken on line 6—6 of Fig. 5.

As shown in Fig. 1, the pneumatic lifting device has a top or upwardly moving member 10 which includes a top annular depending flange 11 which is circular and is provided with a cylindrical interior wall 12. The member 10 also has integrally connected therewith a depending sleeve 13 which surrounds a jack post 14 rigidly held in a vertical position in the concrete being poured, not shown. The sleeve 13 has its inner wall ground to true circular form and is of such a length that the upper member 10 of the pneumatic lifting device will at all times be held vertical to the axis of the jack rod 14.

Formed on the flange 11 are a series of depending socket members 15, 16 and 17 which form abutment seats for bit members 18, 19 and 20.

A second set of bit members 21, 22 and 23 are fulcrumed against a depending flange 24 of the second member 25 of the pneumatic lifting device. The member 25 is formed with a flat upper surface 26 and an opening 27 through the sleeve 13 adapted to surround and embrace the jack rod 14, and guide and hold it in its vertical movements along the jack rod.

As viewed in plan, the longer set of bits 18, 19 and 20 bear at their ends against the abutment ends 28, 29 and 30 upon the ends of socket members 15, 16 and 17. The shorter bits 21, 22 and 23 bear against the downwardly extending flange 24 at 31, 32 and 33 respectively, as clearly appears in Fig. 2.

Directly below and having their inside walls substantially in the planes of the side walls of bits 18, 19 and 20, are pairs of radially disposed ribs 35 and 36, 37 and 38, and 39 and 40, which are rigidly connected to the bottom wall 41 of pneumatic lifter member 25 and also are connected with the downwardly extending flange 24 of lifter member 25.

Upon the top surfaces 26 of lifter member 25 is positioned an annular sealing plate 42 which is provided with an inner annular flange 43 taking against the outer wall of the sleeve 13. The sealer member 42 further has an outer annular flange 44 which takes against the annular wall 45 of the flange 12 of the top pneumatic lifting member 10. There is thus formed an annular chamber 61 between the two members of the pneumatic lifter devices 10 and 25.

In a similar manner the bits 21, 22 and 23 lie inside the planes of pairs of spaced ribs running at their tops into the horizontal plane of the bottom of flange 24, which last named ribs are designated 46 and 47, 48 and 49, and 50 and 51 respectively. These ribs are spaced apart a distance substantially equal to the diameter of the jack rod 14 as is true of the pairs of ribs 35 and 36, 37 and 38, and 39 and 40. The sets of ribs 46 and 47, 48 and 49, and 50 and 51, come opposite outwardly extending lugs 52, 53 and 54 formed integrally with and extending at their bottoms in the plane of the bottom flange 24 of the lower pneumatic lifter member 25.

The arrangement of these sets of ribs is such that there are six sets of them each extending radially and each angularly separated the same distance, the sets of ribs 35 and 36, 37 and 38, and 39 and 40 alternating with the sets of ribs 46 and 47, 48 and 49, and 50 and 51.

Ribs 36 and 47 are connected toward the middle of their lengths by an arcuate member 55. Similarly ribs 35 and 48 are connected by an arcuate member 56, ribs 37 and 49 by an arcuate member 57, ribs 38 and 50 by an arcuate member 58, ribs 39 and 51 by arcuate member 59, and ribs 40 and 46 by an arcuate member 60. The arcuate members 55, 56, 57, 58, 59 and 60 taken together outline a circle and have the effect with the pairs of radial ribs, above defined, of giving great strength to the bottom pneumatic lifting member 25.

The lower surface 62 of the top pneumatic member 10 is spaced a very small distance from the top surface of annular sealer member 42, as indicated at 63 in Fig. 1. However, the annular chamber 61 is widened at its outer limits, as indicated at 64 and 65 in Fig. 1, and into this annular chamber and the space between bottom 62 and sealer plate 42 compressed air may be controllably injected through opening 66 connected with a suitable hose, from a container of compressed air and valve means for permitting periodic injection of the compressed air into the annular chamber 61. This air injecting means is of common and well known construction and, therefore, is not shown.

It will be apparent, however, when air under pressure is admitted through opening 66 into compressed air chamber 61 it will be distributed uniformly over the annular sealing member 42 and will force outwardly its respective flanges 43 and 44 and thus seal the chamber tight against leakage.

The injection of compressed air into chamber 61 will result in expanding the chamber 61 and, because the bits 18, 19 and 20 hold the lower member 25 from downward movement, the expanding of chamber 61 must effect upward movement of the upper pneumatic lifting device 10 which lifts with it the floor and form structure supported on its upper surface, not shown.

As shown in Fig. 1, screwed into a threaded opening 67 in flange 11 of top pneumatic lifter member 10 is a bolt or rod 68 having on its lower end a head 69. The bolt 68 goes freely through an opening 70 in lug 54 on the lower pneumatic lifter member 25 and thus will be constrained to have the vertical movements which the top pneumatic lifter member 10 has and to be movable relative to the bottom lifter member 25 through the opening 70. Bolts 71 and 72 are similarly mounted to move freely through lugs 52 and 53.

The lugs 52, 53 and 54 have arcuate ends and are mounted to have free vertical movement within recesses 73, 74 and 75 in the flange member and the extension 76 thereof, as clearly shown in Figs. 1 and 2.

About each of bolts 68, 71 and 72 are mounted sleeves 77, 78 and 79 which are rigidly connected with the respective lugs 54, 52 and 53. The lower ends of the sleeves 77, 78 and 79 are spaced from the bolt heads 69 a suitable distance, as indicated at 80 in Fig. 1. It follows that as the two pneumatic lifter members 10 and 25 are separated by air pressure if, as is the fact, the lower member 25 is restrained from downward movement by bits 21, 22 and 23, the movement must

be imparted to the upper pneumatic lifter member 10.

This will carry upwardly all the bolts 68, 71 and 72 movable within the sleeves 77, 78 and 79, lifting the bolt heads 69 with the bolts and compressing springs 81 on the bolts between the respective lugs 54, 52 and 53. When, therefore, the pressure is released, letting the air escape, the upper pneumatic lifter member 10 will be held stationary by the dogs 18, 19 and 20 and the springs 81, acting in consort, will push the lower pneumatic lifting member 25 upwardly to initial position.

This operation will normally lift the top member 10 and the parts carried thereby a very small distance each time the air pressure is applied and released. In practice it has been found effective to have this distance from one-fourth to three-eights of an inch. It follows that rapid repetition of the lifting operation will soon produce an over-all lift through any desired distance.

A plate 32, Fig. 1, preferably of a substantially heavy steel, has a central opening 83 by which the plate is mounted upon the jack rod 14. Other openings 84, as indicated in Fig. 1, receive the bolts 68, 71 and 72 so that the plate will then rest upon the bolt heads 69. When in that position the plate 32 anchors the bolt heads to the jack rod 14 and effectively prevents any rocking or swinging thereof which might put sufficient strain on either the flange 11 or the bolts 68, 71 and 72 to cause breakage. This breakage is very effectively prevented by the plate 32 mounted as stated.

The two sets of bits 18, 19, 20, and 21, 22, 23, respectively, are each provided with pins 87 whose opposite ends 85 and 86 are shown projecting outwardly in opposite directions from the planes of the sides of the bits. Member 87 is welded or otherwise permanently secured across the bottom faces of bits 18, 19 and 20, 21, 22 and 23.

Each bit of either type has connected therewith two springs 88 and 89 which extend outwardly of and along the side faces of the bits, as clearly shown, in Fig. 2. At the opposite ends of each spring are loops 90 and 91. At least the loops 90 have a gap 92, as indicated in Fig. 1, which is of sufficient width to permit the loops 90 readily to be withdrawn from the projections 85 and 86 to permit quick and easy removal of the bits.

As shown in Fig. 5, there are two sets of transverse ribs between the sets of respective ribs 35 and 36, 37 and 38, and 40 and 50; and the other set of ribs 46 and 47, 48 and 49, and 50 and 51. The transverse ribs for the first set are designated 93, 94 and 95. The transverse ribs for the second set are designated as 96, 97 and 98. As clearly shown in Fig. 1, the transverse ribs 93, 94 and 95 come out substantially into the plane of the bottom of the flanges 99 and 24 and of the annular sleeve 99 formed integrally with pneumatic lifting member 25.

As clearly shown in Fig. 1, the transverse ribs 96, 97 and 98 project only a short distance from the lower plate 25. The sets of springs 88, 89 for the longer bits 18, 19 and 20 are connected to longer ribs 93, 94 and 95, while the sets of springs for the shorter bits 21, 22 and 23 are connected to the shorter ribs 96, 97 and 98.

Thus, although the shorter bits 21, 22 and 23 engage with their edges 100, the jack rod at a point closer to the pneumatic lifting member 25

than the point of engagement of the edges 101 of the longer bits 18, 19 and 20 with the jack rod, the above arrangement enables springs of the same length to be employed.

The connection of the springs with the bits and the transverse ribs is well shown in the detailed Figures 3 and 4. In both cases the spring loops 90 of the springs 88 and 89 lie in planes parallel with the side walls 102 and 103 of the bits 18, 19 and 20, while similar loops 104 and 105 are in similar planes connected through openings 106 and 107 in transverse ribs 93 (the same in connection with transverse ribs 96, 97 and 98).

As shown in Figs. 1 and 4, the ribs 46, 47, 48, 49 and 50, 51 are cut out part way down, as indicated at 108, to permit the springs 88 and 89 to move in toward the tops of the reduced transverse flanges 96, 97 and 98.

In Fig. 2 the sharpened edges of the dogs 18, 19 and 20 which engage jack rod 14 are indicated by numeral 109. Similar edges 100 of the bits 20, 21 and 22 are provided for engaging jack rod 14 at a higher point thereon.

The advantages of my invention will be apparent from the above description. A principal advantage comes from the use of two springs for each bit connected at the two sides of the bit over projecting members, which as shown, are the ends 85, 86 of transverse cylindrical members preferably welded to the bottom face of the dogs. This insures a very powerful pull from the two springs distributed throughout the width of the bit, and holds the sharpened ends of the bits at the proper angle to engage the jack rod.

Another great advantage resides in the fact that the connection of the springs to full length and shorter transverse ribs on the lower one of the two pneumatic lifter members, one set of ribs being of greater depth than the other set makes possible the use of uniform springs of the same length.

A further important advantage from the above form of attachment is that it enables the springs to be extended very nearly at right angles to the lengthwise extent of the bits, thus greatly increasing the torque pull of the bits against the jack rod.

I claim:

1. In a jack for elevating forms and floors during the pouring of concrete, a jack rod along which the jack is adapted to move, a two-part pneumatic lifting member including an upper part having a depending flange forming within it a chamber and a lower part movable along said flange, said lower part being formed with two sets of separated pairs of substantially radial ribs spaced apart, a transverse flange between each pair of ribs of one set extending to the top plane of said radial ribs and forming an abutment therebetween on the lower member, a flange between each pair of the second set of radial ribs extending only part way to the tops of said radial ribs, each of said flanges of both sets having formed therein two suitably positioned openings the upper member having downwardly extending parts forming abutments, two sets of clamping bits each free from permanent attachment to any part of the jack, the bits of one set adapted to have one end engage in abutment on the lower lifting part and the bits of the other set adapted to have one end engage an abutment on the upper lifting part, the other ends of all the bits being sharpened for engagement with the jack rod, members secured to the

bits at near their bottom sides and projecting outwardly from said sides, a pair of springs for each bit connected at one end in said openings and removably connected at their other ends with said projecting members for holding the sharp edges of each pair of bits in contact with the jack rod.

2. In combination with a vertically extending jack rod, a jack comprising a first plate surrounding said rod having an annular depending flange on the outer lateral limits forming a chamber in the lower surface of said plate, a second plate surrounding said rod and formed to fit within the chamber of the first plate with its top surface substantially contiguous to the bottom surface of the first plate, a resilient connection extending between said first and second plates and forming a follow-up connection between said plates, two sets of clamping bits supported beneath said plates having sharpened ends engaging the jack rod, one of said sets extending from the depending flange of the first plate to anchor said plate to the jack rod during relative movement of the second plate, the other of said sets extending from the second plate to the jack rod to anchor said plate to the jack rod during relative movement of the first plate, projections extending laterally from each of said bits adjacent their sharpened ends, flanges depending from the lower surface of the second plate, and two springs extending between the projections on each bit and the flanges on the lower surface of the second plate and in a plane nearly parallel to the axis of the jack rod to bias the sharpened ends of the bit against the jack rod.

3. In combination with a vertically extending jack rod, a jack comprising a first movable member encompassing the jack rod, a second movable member encompassing the jack rod beneath the first member, said first member being movable relative to the second member, a resilient connection extending between said first and second members forming a follow-up connection between said members, two sets of clamping bits supported beneath said members having sharpened inner ends engaging the jack rod, one set extending angularly from each of said members to anchor the respective member to the jack rod during relative movement of the other member,

projections extending downwardly from the second movable member adjacent each of the clamping bits, and a pair of springs extending from either side of each of said clamping bits adjacent their sharpened ends to said projections and in a plane nearly parallel to the axis of the jack rod to bias the sharpened ends of the bits against the jack rod.

4. In combination with a vertically extending jack rod, a jack comprising a first plate surrounding said rod having an annular depending flange on the outer lateral limits forming a chamber in the lower surface of said plate, a second plate surrounding said rod and formed to fit within the chamber of the first plate with its top surface substantially contiguous to the bottom surface of the first plate, a third plate surrounding said rod and spaced below the second named plate, a plurality of headed guide rods depending from the annular flange of the first plate penetrating the second plate and the third plate with the heads engaging the lower surface of the third plate, a spring on each guide rod extending between the third plate and the second plate and biasing the second plate in the direction of the first plate, a first set of clamping bits having sharpened ends extending from the annular flange of the first plate to the jack rod above the third plate, a second set of clamping bits of shorter length than the first set having sharpened ends and extending from the bottom surface of the second plate to the jack rod above the third plate, projections extending downwardly from the second plate adjacent each of the several clamping bits, and a pair of springs extending from either side of each of the clamping bits adjacent their sharpened ends to said projections and in a plane nearly parallel to the axis of the jack rod to bias the sharpened ends of the bits against the jack rod.

40
